UNITED STATES PATENT OFFICE.

THOMAS G. HAWKES, OF CORNING, NEW YORK.

DESIGN FOR THE ORNAMENTATION OF GLASS VESSELS.

SPECIFICATION forming part of Design No. 21,705, dated June 12, 1892.

Application filed June 16, 1892. Serial No. 436,989. Term of patent 14 years.

To all whom it may concern:

Be it known that I, THOMAS G. HAWKES, a citizen of the United States, residing at Corning, in the county of Steuben and State of New York, have invented and produced a new and original Design for the Ornamentation of Glass and other Vessels, of which the following is a specification, reference being had to the accompanying drawing, forming part thereof, and which is a bottom view of a glass dish, showing my design.

The leading features of my design consist of the large double-lined cycloidal figures presenting continuous lines and the appearance of radial leaves and the large fan figures between the outer portions of the leaves, thus forming what I call the "coronet" design.

1 are double-lined cycloidal figures presenting continuous lines and the appearance of leaves extending radially from a common 20 center. Between the outer portions of the leaves are large fan figures 2. The body portion and leaves are ornamented with rosette figures 3, arranged in quincunx form.

Having thus described my invention, the 25 following is what I claim as new therein and desire to secure by design Letters Patent:

The design for the ornamentation of glass and other vessels, substantially as herein shown and described.

THOMAS G. HAWKES.
